22 Claims. (Cl. 68—21)

1

My invention relates to clothes washing machines or devices, exemplified herein as applied for household laundry purposes, and particularly to improvements in such machines relating to means for drying and draining water from the clothes.

This application is a division of my copending application for Washing Machines, Serial No. 306,797, filed November 30, 1939, now Patent No. 2,407,660, dated September 17, 1946.

In devices of this character heretofore suggested, many factors have entered into the problem of rendering them simple, effective, economical and more desirable over a wide field of use, among which are such elements as the construction of drying and draining means, the particular manner of flushing and drying the clothes, and other features which must be properly combined and operated together to produce a machine that is efficient, easy to use, and free from trouble.

It is among the objects of my invention to overcome prior deficiencies in such apparatus and to produce a machine in which are novel constructions and arrangements of tub, agitator means, drain facilities and means for compressing the clothes to dry the same.

Another object of the invention is to provide a top construction for a washing machine of the upright tub type, that is novel in the provision of screen means at the inner side of the lid toward which the clothes are moved for flushing, and against which they are pressed for drying, and in certain elements of the screen, the lid and the tub top.

Another object of the invention is to provide a novel and self cleaning arrangement for conducting water out of the tub during operations of flushing and of drying the clothes.

Another object of the invention is to provide a dryer of the diaphragm type that advantageously is molded or otherwise constructed to conform to agitator means in the tub, and that has novel relation to the tub.

Another object of the invention is to provide means which, upon expansion of the diaphragm, increases molding and sealing effects between the diaphragm and the tub.

With such objects in view, as well as other advantages which may be incident to a utilization of the improvements, individually or in combination, the invention comprises the elements and combinations thereof herein set forth and claimed, with the understanding that the several necessary elements constituting the same may be varied in proportion, arrangement and texture without departing from the spirit and scope of the invention as intended, and as set forth in the drawings, specification and claims.

2

In order to render the invention more clearly understood, means are shown in the accompanying drawings for carrying the invention into practical effect, without limiting the improvements to the particular constructions which for the purpose of explanation, are made the subject of illustration.

In the drawings:

Figure 1 is a front side view, partially in elevation and partially in substantially central vertical plane section of a washing machine of a particular type constructed in accordance with the invention;

Fig. 2 is a horizontal sectional view, taken substantially along the line 2—2 of Fig. 1;

Fig. 3 is an enlarged detail sectional view of parts appearing at the upper right-hand portion of Fig. 1;

Fig. 4 is a slightly enlarged detail view, in side elevation, of a screen structure shown at the top of Fig. 1;

Fig. 5 is a top plan view showing a modified form of screen for position in the structure in the place of the screen of Fig. 4;

Fig. 6 is a view, on a slightly enlarged scale, similar to the top of Fig. 1, showing the modified screen of Fig. 5 and its mounting; and

Fig. 7 is a sectional view, on an enlarged scale, taken substantially along the line 7—7 of Fig. 2.

30 Machine in general

Referring particularly to Figs. 1 and 2, the example of the machine therein illustrated comprises a lower base 26, an upper stationary housing 27 on the base 26, an oscillatory tub 28 disposed generally in the housing 27, but having a special top or lid structure 31 extending above the housing, an agitator 83 having baffle elements or means 32 at the bottom of the tub and separate agitator baffles 34 near the top of the tub, for agitating the clothes and water in the tub during washing, flushing, and rinsing actions, a diaphragm 33 in the tub for effecting flushing and drying actions by expansion of the diaphragm, a valve 36 under the tub for admitting fluid behind the diaphragm and in part controlling operation of the diaphragm 33, a tub oscillating means or mechanism enclosed in a casing 41 supported by the base 26, and suspension means 42 for the casing 41 associated therewith.

The base structure 26, which may be any one of several different types has legs 51, at least two of which, as seen in Figs. 1 and 2, are suitable in location and construction for cooperation with the suspension means 42, as will later be described. The legs 51 are joined at the lower ends, as by tie rods 53, and support at their tops a metal or other disc or plate 56.

The plate 56, in this instance, is surmounted by a shell or ring 57 having a horizontal peripheral top flange 58 for attachment to the housing 27, and a peripheral bottom flange 61 telescoping and suitably held to the plate 56.

The housing 27 encloses the tub 28, and other parts, and receives wash and rinse water ejected from the top of the tub, as will later appear. Pipe 62, extending from the bottom of the housing and through the plate 56, is provided for 10 draining the housing 27. The housing comprises a thin sheet of metal lower cup like portion 63, having an upper vertical peripheral flange 68 to which is secured an upper thin sheet metal cylindrical member 71. At its upper end, the 15 cylinder 71 is provided with an annular thin sheet metal shell or cap 72 having an offset perimeter 73 secured to the top periphery of the cylinder 71. The remainder of the cap 72 is of substantially half round section, forming a relatively large upwardly convex bead or toroid, having a relatively small radially inwardly extending flange 77 about the upper part of the tub 28 and in closely spaced relation thereto. A bushing 78 is provided in an opening in the shell 72, 25 for a purpose to be hereinafter set forth.

The tub

The tub 28 is of the oscillating type for operation about a vertical axis, relative to which its sheet metal body 79 is of somewhat elongated globe shape having a clothes receiving opening at its top, and being shaped at its upper and lower portions for the reception of, and cooperation with, the baffle elements 32 and 34 of the agitator means which will be later described.

The tub has a portion 81 pressed upwardly at the center of the tub bottom (Fig. 1). A disc-like metal mounting element 82 is provided outside the tub bottom, and the agitator 83 has a disc-like base 84, provided inside the tub bottom, these elements extending about the portion 81, and conforming to and being secured to the tub as by rivets (not shown).

The bottom mounting 82 has a recess for the 45 reception of the upper end of a drive shaft 87, which is operatively connected to the mounting 82, as indicated by a pin 88 and to the oscillating drive mechanism 41. The lower portion of the tub also has an aperture in which is secured the bushing 89 of a valve 36, for controlling the movements of the diaphragm.

Any suitable mechanism may be provided for oscillating the tub, the details of one such mechanism being shown in my aforesaid copending 55 application. Such mechanism is enclosed in the casing 41.

Bolts 288 secure to the casing 41 laterally extending plates 291 which are connected to leaf springs 292, of the suspension means 42, which, in turn, are secured to two of the legs 51 of the machine.

At about its vertical central portion, the tub is provided with a peripheral channel 92, Fig. 1, open at the inner side of the tub and constituting part of means for attaching the diaphragm 33 to the tub, as will further appear.

The top of the tub has secured thereto a metal casting forming a neck portion 96, of cylindrical or ring-like character, having a depending tapered flange 97 conforming, at its outer surface, to the inner surface of the sheet metal body 79 of the tub, and having its inner surface gradually merging and curving into the curved inner surface of the sheet metal body, whereby to pre-

serve the gradually rounded inner top contour of the tub. The neck portion 96 has an outwardly projecting peripheral flange 102 (Fig. 3) in which is a top groove 103. A plurality of peripherally spaced ducts or outlet ports 106 extend diagonally downwardly and outwardly through the casting 96 from the groove 103 to the exterior of the tub, for allowing water from the tub to drain into the housing 27 through the radially narrow peripheral space between the flange 77 on the shell 72 and the upper part of the tub.

A plate like element 111 of the lid structure 31 is of inverted shallow substantially dish shape. The metal of the plate at its periphery encircles a ring 113, in this instance of square cross section, which forms a flange that overlies and cooperates with the flange 102. Mounted concentrically with the ring 113 is an annular 20 clamping frame 132 having a peripheral inner lip 114 between which and the lid 111 is disposed a rigid screen element 133 conforming in general to the shape of the plate 111. The frame 132 is appropriately secured to the lid and has peripherally spaced, downwardly extending ducts 134 which communicate at their lower ends with the peripheral groove 103 and at their upper ends with the screen openings.

The screen 133, as better seen in Fig. 4, is of 30 large mesh and also has radial grooves or corrugations 135, which when the clothes mass is pressed against the screen by the diaphragm, form gutters or channels for better draining off the water outwardly through and around the annular space between the lip 114 of the ring 132 and the plate 111, the water draining downwardly through the ducts 134 into the top annular groove 103, and thence through the ducts 106, into the housing 27, as above mentioned. Of course, before the clothes are tightly pressed against the screen, the main bulk of the wash or rinse water being displaced by the diaphragm flows freely outwardly through various parts of the screen, irrespective of the grooves 135. Although the drawings show the ducts 106 and 40 134 substantially in register, the groove 103 and the ducts 106 may be of sufficient capacity to carry off the water admitted to the groove by the ducts 134 irrespective of the location of the ducts around the groove. Obviously, grooves or corrugations, similar to the grooves or corrugations 135, may be provided in the lid element 111, in addition to, or instead of, those in the screen 133.

The plate 111 is removably held upon the tub by a clamping ring 117 of channel section, which embraces the lid flange 113 and the tub flange 102, when the lid is in place on the tub. The ring is split, as at one position about its periphery, and provided with operating means for peripheral expansion of the clamping ring to release the lid for opening, and for peripheral contraction of the ring for locking the lid in closed position.

At the top outside center of the plate 111, an aperture therein is surrounded by a nipple 136 55 (Fig. 1) attached thereto and on which is a grooved ferrule 137. A cap-like member 138 is in rotative water sealed relation to the nipple, being provided with a spring clip 143 engaging the groove of the ferrule and the inner end of which removably extends through an opening in the cap. The cap 138 is connected, by a coupling 139, to a flexible conduit 140, which extends through the bushing 78, and between the housing 27 and the tub 28, to a nipple 141 in the bot-

tom wall of the housing. Water is supplied to the conduit 140 from an inlet connection 142, secured to the bottom disc 56, through a hose or conduit 144, which extends through an opening in the shell 57, to a valve of an automatic control mechanism (not shown), and from the valve through a hose or conduit 149, to the nipple 144.

A section 151 of the conduit 140 operates as a hinge, or flexible mechanical connector, between the housing 27 and the lid 31, to prevent complete separation of the lid from the tub when the lid is open, and to hold the lid in convenient position for closing the tub. Also, the section 151 of the conduit 140, may move back and forth through the bushing 78 to avoid buckling of the conduit and to better control the action of opening and closing the tub.

The tub, as above described, thus has its main body and lid constructed and arranged relative to each other to render the body capable of receiving and confining a substantially full tub of clothes while the cover is open, rendering it unnecessary to manipulate the clothes in closing the lid, and in conjunction with a novel diaphragm for squeezing the clothes dry, and novel screen means against which the clothes are squeezed, generally improves the machine.

The agitator means

Although agitation or stirring of the clothes and water may be obtained by agitating means operating relative to a stationary tub, in the example here given, it is obtained by baffles fixed to the oscillating tub, whereby the water and clothes are given a special tumbling action substantially in accordance with the arrows D. Either or both sets of baffles 32 and 34 may be employed, and either or both may be formed in the tub by being pressed therein, and may be of any desired shape.

The upper baffles 34 are herein shown as integral parts of the top metal casting 96, although they may be separately attached thereto, or to the tub, or constitute parts of the tub body as indicated, and may be varied in number, two being shown, located at opposite sides of the tub. They are of fin-like character rounded at the inner thinner edges 156 which, as indicated in Fig. 1, slope downwardly and inwardly from the casting 96, substantially as chords of the cross sectional arc of the tub body 79, to a position close to the mid-channel 92, where they are suddenly sloped into the tub surface. Each fin has a lower, broad side 157 which is tapered downwardly and outwardly from the edge 156 and, at its lower edge, merges gradually into the inner surface of the tub body. Each fin also has an upper side 158 which is straight so as to present a flat, radially extending side. The flat sides of the baffles 34 face in the same direction with respect to the direction of tub oscillation, for a purpose to be referred to later.

The broad sides of the baffles extend in a general radial direction to the tub axis at any horizontal section, but are inclined upwardly, and, longitudinally, they slope relative to the vertical at an angle of about twenty-five degrees.

The lower agitator 83 (Figs. 1, 2 and 7) comprises the disc-like base 84, on which are a plurality of baffles 32 which extend radially from the center. At the upper edge, the baffles are rounded, and the sides are divergently tapered to the base. In vertical plane outline each baffle is of generally curved or rounded contour conforming somewhat to the lower recess of the tub, and has an outer enlarged portion 163. These baffles, in relation to such recess and to the

globular rising sides of the outer portions of the tub, cause the water and clothes mass to be impelled radially outwardly and upwardly along the sides of the tub, which mass, if uninterrupted, would move downwardly in the center thereof of the tub, round and round. However, at the top, the clothes encounter the additional agitation produced by the upper baffles 34, which will break up the cycle produced by the lower agitator, and keep the clothes well spread out in the water so that all clothes receive the full agitation, which is a combination of actions.

During rinsing, the central downward movement of the clothes may be augmented by the fresh rinse water entering the tub, in the direction of the arrow E. At the same time, the fresh water is introduced and mixed in definite and symmetrical manner, ensuring its diffusion to all parts of the clothes mass, and avoiding rinsing more at one part than at another.

In addition to the described actions of the upper baffles 34, they perform a further function in augmenting the thorough cleansing action on the entire clothes mass. Since the tub oscillates on a vertical axis, and the baffles have flat sides facing in the same direction, as these sides move forwardly, they engage the clothes mass and move it part way around the tub circumferentially to occupy a different position with respect to the main forces exerted by the lower baffles. As these baffles move in the reverse direction, the clothes mass slides off the slanting faces thereof. The next forward motion of the flat sides of the baffles engages a different portion of the clothes mass, and thus the clothes are moved around the vertical axis with a step by step motion, in addition to all the other movements imparted thereto.

Diaphragm

40 Other pressure diaphragms or contracting chamber type drying means have been heretofore suggested, but not in the form herein developed or with the advantages as will appear. In the present instance also, the diaphragm is employed as means for drying the clothes, and also may be employed as means for effecting a flushing action.

45 The diaphragm 33 hereof is made of high grade durable soft rubber, or other material having sufficient weight, body or thickness to be firm and positive in action, of long life, and sufficiently flexible to ensure its ready response to expansion and contraction, as well as its ready conformation to the clothes mass whereby to insure uniform effective pressure thereon. It also is molded or formed such that, in its contracted or relaxed state, it not only conforms closely to the shape of the tub, but also to the agitator baffles 32, and to other parts of the lower agitator 83.

50 The diaphragm is somewhat semi-spherical or cup-like in shape, conforming, in general, to the inner lower sides of the tub 28, and having an upper edge peripheral extension or bead 161, Fig. 1. An expansion ring 171 engages an upper peripheral part 172 of the diaphragm, under the bead 161, pressing the part 172 into the channel 92 formed in the tub side wall; this ring having sufficient expansive force to hold the diaphragm 33 securely in place, but not necessarily enough in all instances to in and of itself provide a perfect water seal against the pressures imposed thereon. When the diaphragm is expanded upwardly, especially to its utmost upper positions during 55 the drying operation, which action tends to turn

it inside out, the diaphragm wraps itself about the ring 167. Downward slippage of the top edge of the diaphragm is prevented by the bead 167, and with the pressure now exerted on the inner side of the ring by the diaphragm, it acts on the ring with a substantially snubber effect, and thus increases the sealing effect of the part 172 and the extension 167, against the tub body 19 in and about the channel 92, and the ring 171.

At its bottom (see Figs. 1, 2 and 7), the diaphragm is further provided with portions or pockets 168 of inverted substantially channel section closely conforming to, and in relaxed condition fitting over, the baffles 32. During expansion, the diaphragm lifts off the bottom of the tub, rising from the baffles and, since it does not turn relative to the tub, returns easily and accurately to position fitting the baffles; this action being ensured by the wider open lower portions and the gradually curved lower edges of the channel sections of the diaphragm, conforming to the curves of the baffles joining them to the base 84.

The flow of water, to and from the space between the diaphragm 33 and the bottom of the tub to expand and contract the diaphragm, is controlled by the diaphragm valve 36, indicated in Fig. 1. Water under pressure is admitted by the valve 36, through the bushing 89 to position under or behind the diaphragm, to push or expand the diaphragm upwardly in the tub.

The water supply to the valve 36 is from an inlet pipe 211 (Fig. 1) secured to the disc 56 by a clip 212, through a conduit 216, which extends through an opening in the shell 57 to a valve of an automatic control mechanism, not shown. From the latter valve, the water is conducted through a conduit 181, which, after entering the shell 57, extends through a nipple 226 in casing portion 63 and is formed into a flat spiral section 227, of about two turns surrounding the drive shaft 87, before continuing to the valve 36. The turns of the spiral are of relatively large diameter and adapted to radially contract and expand so that the tub may oscillate without adversely affecting the fluid connections by reason of the relative movement between the tub carried valve 36 and the stationary nipple 226. Arranging the conduit section 227 in a flat spiral coil, also allows the bottom of the tub to be spaced from the bottom of the housing by a minimum distance, whereby to conserve space at a place where such conservation is of importance in a selection of a height for the housing.

As the clothes are compressed between the diaphragm and the screen 133, the wash or rinse water escapes from the top of the tub. Near the end of the drying operation, the pressure behind the diaphragm builds up to that of the incoming fluid. When the water supply has been stopped by the aforesaid automatic control mechanism, a bleeder valve of the valve 36 allows the water pressure in the valve casing to drop only gradually. After a certain amount of bleeding, during which the water pressure drops sufficiently in a few seconds, the valve 36 opens wide to release the water and pressure behind the diaphragm. The normal contraction of the diaphragm 33 also forces the water through the valve 36 into the bottom of the housing 27, from which it drains through the drain pipe 62. The water pressure applied behind the diaphragm during expansion of the latter being substantially uniform, the pressure developed in the drying and flushing operations are readily calculable, so that the valve 36 may be properly adjusted to effect

the desired draining, quickly and in proper sequence.

The pressure maintained by the adjustable bleeder of the valve 36 also enables regulating the duration of the period of high pressures on the clothes, that is to say, the rate of bleeding can be adjusted to determine the length of time before the valve 36 opens to dump the water from behind the diaphragm and, therefore, there may be a period of sustained higher pressures during the drying operation.

Special provisions are made to insure complete draining of the water from behind the diaphragm 33, and to insure against accidental and premature closing of the opening to the diaphragm valve. To this end, the lower face of the base 84 of the lower agitator has an annular groove 228, Fig. 1, having a peripheral portion 229. The head of the mounting bushing 89 for the diaphragm valve 36 is received in the groove 228. The base 84 has apertures 234 therethrough communicating with the groove 228, and the peripheral portion 229 also has apertures 232 communicating with the groove 228. When water is admitted behind the diaphragm, it passes through the apertures 232 and 234 to start the diaphragm expansion. When the water is being expelled from below the diaphragm, it drains through the apertures 232 and 234 into the groove 228 and from the latter through the valve 36 to the tub housing 27, but without danger of the diaphragm fouling the opening into the diaphragm valve 36.

Operation

At the beginning of the operation of the machine, the operator places the dry clothes in the tub. The machine is next filled with water and after soap, washing powder or water softener is added, the lid 31 is locked in place and tub oscillation started.

At the end of a selected washing time period, the automatic control mechanism may operate to admit the water behind the diaphragm 33, through the valve 36. This action is the beginning of a flushing operation in this case, in which the diaphragm lifts the clothes and wash water toward the top of the machine, so that the wash water is gradually forced out through the drain openings 134, in the lid, and the openings 106, in the tub. Thus, any scum and matter which has accumulated on top of the water is flushed out of the machine. At this time, the agitation of the machine has not stopped, and does not stop until the diaphragm has lifted the clothes and water past the center of the tub, which is about one-half or two-thirds of the flushing cycle, so that agitation continues, by means of the upper baffles, and the accumulated matter is liberated from the clothes to float off with the water. The expansion of the diaphragm is continued until substantially all of the wash water has been extracted from the clothes, at which time the valve 36 operates to empty the water from behind the diaphragm, and the diaphragm returns to its lower position shown in Fig. 1.

The control mechanism next operates to admit water to the tub through the center of the lid to begin the rinsing operation. When sufficient water has been admitted to the tub to make agitation of the clothes and water of some benefit, which is about one-third of the time consumed by the rinsing operation, agitation is started. Agitation continues during the remainder of the

rinsing operation, and for a sufficient length of time for the tub to completely fill with water and also to overflow through the ducts 134 and 106 for a sufficient interval of time to thoroughly rinse the clothes.

At the conclusion of the rinsing operation, the control mechanism again admits water through the diaphragm water valve 36 to again expand the diaphragm to eject the rinse water, and this is the beginning of the drying operation. Agitation may be continued until the diaphragm is above the center of the tub, and preferably during about half of the period of time for this particular operation of the diaphragm. The expansion of the diaphragm continues to bring about drying of the clothes by compressing the same against the upper portions of the tub and its cover, until all of the water is extracted from the clothes, whereupon the supply of water behind the diaphragm is shut off. Then, the diaphragm valve 36 will operate to dump the water from behind the diaphragm, as above described, after which the machine is stopped, whereupon the operator removes the lid from the machine and takes out the washed and dried clothes.

Modified screen structure

As shown in Figs. 5 and 6, in which corresponding parts are designated by corresponding reference numerals having the suffix (a), and new parts are designated by numerals alone, a modified form of the screen 133, in a lid 31a of the machine, comprises a screen 133a, which, instead of being constituted of wire mesh, as in the case of the screen 133, is constructed of sheet metal, such as stainless steel. It has the same general inverted shallow substantially dish shape, but instead of requiring the removal of screws or other parts for its removal, the screen 133a is provided with a depending peripheral portion 526 having a bead 527 which interlocks with a bead 528 on a ring 132a of the lid. Thus, the screen is adapted to be moved into position and removed with a substantially snap action. The ring 132a has apertures 134a communicating with a groove 103a in the top surface of a tub neck portion 96a, which is further provided with ducts 106a. A bail member 117a embraces flanges 113a and 102a, to hold the lid in place, as hereinabove described. Apertures 529 in the screen 133a take the place of the openings in the wire screen mesh above set forth, and a central aperture 531 is provided in register with the inlet nipple 136a. Raised portions 532 serve to maintain the screen 133a spaced from the lid plate 111a. Portions similar to the portions 532 may, of course, be provided on the lid element 11a, in addition to, or instead of the portions 532 on the screen element 133a.

Other modifications may be made in the shape, arrangement and location of parts within the spirit and scope of my invention, and such modifications are intended to be covered by the appended claims.

I claim:

1. In a washing machine, a tub, a diaphragm support disposed peripherally of the tub, a flexible diaphragm held peripherally between said support and the tub and extending in one direction axially of the tub from said support, and means for flexing the diaphragm in the opposite direction across the position of the support and causing it to cooperate with said support in effecting a sealing action.

2. In a washing machine, a tub having a cover

75

receiving portion and a side wall, an inwardly open groove around the side wall of the tub intermediate the top and bottom thereof, an expansion ring around the inside of the tub wall opposite the groove, and a flexible diaphragm of substantially bowl shape having an open end peripheral portion clamped in said groove by the ring.

3. In a washing machine, a tub, an agitator in the tub, a flexible diaphragm in the tub having a normal position in which portions thereof substantially conform to the tub and the agitator, means for expanding the diaphragm, and means for sealing the diaphragm to the tub.

4. In a washing machine, a tub having a lid opening, a flexible diaphragm in the tub for expansion toward said opening, a lid for the opening, a screen mounted at the inner side of the lid against which screen the diaphragm presses clothes in the tub to extract water therefrom, said screen having portions thereof acting as radial channels at the lid side of the screen, and ports communicating with the channels for the discharge of the water pressed by the diaphragm from the clothes.

5. In a washing machine, a tub having a lid opening, a flexible diaphragm in the tub for expansion toward said opening, a lid for the opening, a screen at the inner side of the lid against which screen the diaphragm presses clothes in the tub, and means spacing the screen from the lid and bracing it against the pressing action of the clothes.

6. In a washing machine, a tub having a lid opening, a lid receiving seat around said opening having a peripheral groove therein and outlet ports from such groove, a lid cooperating with said seat and having outlet ports therein also communicating with said groove, and a screen mounted at the inner side of the lid through which water may flow through said ports.

7. In a washing machine, a tub having a neck portion defining a lid opening, a peripheral groove in the neck portion, discharge ports communicating with the groove and extending to the outside of said tub, a lid fitting upon said neck portion, discharge ports in the lid communicating with said groove, a screen in said lid for the discharge ports, a diaphragm mounted in said tub, and means for expanding the diaphragm to lift the articles in the tub and the water toward the lid so as to discharge the water through said ports.

8. In a washing machine, a tub, an agitator in the tub, and a flexible diaphragm mounted in the tub and having portions normally conforming to the agitator.

9. In a washing machine, a tube having an upright axis and a bowl-like bottom portion, an agitator comprising baffles extending transversely of the upstanding tub axis and having upright side surfaces, and a flexible diaphragm molded to a shape substantially conforming to and fitting the baffles and the inner bowl-like surfaces of said bottom portion when said diaphragm is in its position of rest.

10. In a washing machine, a tub having an upright axis and a bowl-like bottom portion, an agitator mounted in the bottom portion and comprising baffles extending transversely of the upright tub axis and having upstanding side surfaces, and a flexible diaphragm in the tub having portions molded to a shape substantially fitting the agitator.

11. In a washing machine, a tub, a molded

flexible diaphragm of substantially bowl shape and having a plurality of portions projecting upwardly from the bottom constituting partitions of inverted substantially channel section extending radially of the vertical axis of the bowl, and means for holding the diaphragm in said tub.

12. In a washing machine, a tub, an agitator having a substantially disc-like element mounted adjacent the bottom of the tub, a flexible diaphragm mounted in the tub and fitting about said agitator, said disc having an annular groove on the under surface thereof, perforations in the disc communicating with said groove, and a valve for admitting fluid in back of the diaphragm and mounted in the tub so as to communicate with said groove.

13. In a clothes washing machine, the combination of a tub, agitator means fixed to the tub, means for oscillating the tub, means opposite said agitator means against which the clothes are pressed in drying, means for pressing the clothes as aforesaid including a flexible diaphragm which, in contracted condition, has a portion constituted as a lining for said agitator means providing for the agitation of the clothes by the agitator means through the intermediary of said lining and, in its expanding action, removes said lining from the agitator means, means securing said diaphragm to the tub to provide for such action, means for expanding and contracting the diaphragm, and means for receiving and draining water from the tub as it is pressed from the clothes.

14. In a clothes washing machine, the combination of an upright tub including a plurality of agitator elements fixed thereto and extending upwardly of the tub bottom spaced from each other about the upright axis of the tub, means for oscillating the tub, means above said elements against which the clothes are pressed in drying, fluid operated means for pressing the clothes as aforesaid including a flexible diaphragm which, in contracted condition has portions fitting about said agitator elements and, in its expanding action, removes said portions from said elements, means securing said diaphragm to the tub to provide for such action, means for expanding and contracting the diaphragm, means below the said diaphragm for exhausting said fluid, and means for receiving and draining water from the tub as it is pressed from the clothes.

15. In a clothes washing machine, the combination of an upright tub including a body having a top opening surrounded by cover seating means, a cover for said opening including seating means for seating on said first seating means and means against which the clothes are pressed for drying, means for oscillating the tub, a stationary housing for the tub providing a slight space between the tub and the housing below said cover, and means for pressing the clothes as aforesaid, at least one of said seating means including means for passing water from the clothes as so pressed and draining it from the tub through said space.

16. In a washing machine, a tube, a flexible diaphragm, a clamping means for holding and sealing the diaphragm relative to the tube, and means for expanding the diaphragm and thereby causing it to coat with said clamping means for increasing the sealing effect thereof.

17. In a washing machine, a tub having an opening through which clothes are inserted into

and removed from the tub, annularly disposed drain means surrounding said opening and including a plurality of spaced ports around said opening, means for pressing the clothes toward said opening, perforate means mounted across said opening and through which water from the clothes is forced, said perforate means being movable to a position to afford access to the tub.

18. In a washing machine, a tub having an opening through which clothes are inserted into and removed from the tub, annular drain means comprising a covered channel surrounding said opening, and means for compressing the clothes to remove water therefrom, at least some of which water enters said annular drain.

19. In a washing machine, a cabinet, a tub positioned in and spaced from said cabinet and having imperforate side walls, an opening in said tub through which clothes are inserted into and removed from the tub, a perforate closure means for said opening, means for compressing the clothes to remove water therefrom, at least some of which water passes through said closure and overflows the tub into said cabinet, and means for draining the water from said cabinet.

20. In a washing machine, a substantially spherical tub having an opening for the insertion and removal of clothes in the tub, a bowl shaped diaphragm secured in said tub and forming a lining for the lower part thereof, baffle means in the upper part of the tub, means for moving the baffle means for agitating clothes and water in the tub, and means for admitting fluid behind said diaphragm to lift the same to compress the clothes against said tub and baffle means to remove water therefrom and to bring the clothes to a semi-dry condition, at least some of which water flows out of the tub through said opening.

21. In a washing machine, a tub, an agitator mounted therein, a flexible diaphragm mounted in the tub and overlying said agitator, means for admitting fluid behind the diaphragm to expand the same and for removing the fluid after expansion of the diaphragm, and means for removing fluid trapped about said agitator.

22. In a washing machine, a tub, an agitator mounted therein, a flexible diaphragm mounted in the tub and overlying said agitator, means for admitting fluid behind the diaphragm to expand the same and for removing the fluid after expansion of the diaphragm, and perforations in the agitator for removing water trapped about said agitator.

GEORGE C. GRAHAM.
